JAMES C. KUTZNER, OF SOUTH PASADENA, CALIFORNIA, ASSIGNOR TO MONARCH INVESTMENT COMPANY LIMITED (A TRUST ESTATE), OF LOS ANGELES, CALIFORNIA

WATER FEED REGULATOR

Application filed January 8, 1929. Serial No. 331,025.

This invention relates to boiler apparatus, and especially to apparatus designed to supply water to the boiler automatically upon the water level receding to a definite point; 5 and also designed to produce a visual or audible signal when the water level is dangerously low.

Such apparatus in general is well known. In one type, use is made of the fact that the 10 steam above the water in the boiler is at a higher temperature than the water. When the water level recedes, steam replaces water in an expansible tube, as for example, of brass or copper. This causes the tube to be 15 raised to a higher temperature than before; and in expanding, it causes the performance of definite control functions, such as successively the act of admitting water to the boiler; and the transmission of a signal, 20 warning that the water level is low.

Such devices are shown in many prior patents; for example, in Bullard, 641,832 of January 23, 1900; also in Witt, 1,012,782 of December 26, 1911; and in Chafer, 512,804 of 25 January 16, 1894. My present invention is an improvement over these references.

In such prior devices, the water is admitted through a valve that is opened automatically by the expansion of the tube. 30 There is a tendency for the valve to hunt between open and closed position. It is an object of my invention to correct this fault.

It is also another object of my invention to provide a novel form of low water alarm. 35 My invention possesses many other advantages, and has other objects which may be made more easily apparent from a consideration of one embodiment of my invention. For this purpose I have shown a form in the 40 drawings accompanying and forming part of the present specification. I shall now proceed to describe this form in detail, which illustrates the general principles of my invention; but it is to be understood that this 45 detailed description is not to be taken in a limiting sense, since the scope of my invention is best defined by the appended claims.

Referring to the drawings:

Figure 1 is an elevation of a system embodying my invention;

Fig. 2 is a sectional view, taken along plane 2-2 of Fig. 1;

Fig. 3 is a sectional view, taken along plane 3-3 of Fig. 1; and

Fig. 4 is a detail section of a portion of 55 the low water alarm mechanism incorporated in my system.

In Fig. 1, I show the outline of a steam boiler 11. This boiler is shown as having the conventional water gauge 12, connected 60 to the boiler as by piping 13 and 14. Water is arranged to be supplied to the boiler through a pipe 15. This pipe is manually controlled, as by valve 16. It also has a check valve 17. If the boiler is to be fed 65 with water manually, the feed pipe 15 can be opened when desired at valve 16, and the valve can be closed when sufficient feed water has been passed to boiler 11.

However, provision is made for alternate 70 automatic control of the feed water. For this purpose, a pair of branch pipes 18, 19, on opposite sides of a valve 20 in pipe 15, lead to an automatically actuated valve 21. With valve 16 continuously open, and valve 75 20 closed, the feed water must pass through branch 19, valve 21, branch 18 and valve 16 before entering boiler 11. And this passage can take place only when valve 21 is opened, 80 in a manner to be hereinafter described, and in response to a lowering of the water level to a definite point.

The structure of valve 21 is shown most clearly in Fig. 2. The body 22 is shown as a casting, the interior having an apertured 85 partition 23. This partition carries a ground valve seat 24. A valve closure member 25 is arranged to be seated thereon, thereby interrupting the passageway between pipe 19 and pipe 18. It is to be noted that this 90 closure 25 is shaped like a door knob; it is a solid of revolution, forming a doubly curved surface. This form of closure is of considerable importance, and will be further referred to hereinafter.

The valve closure 25 has a stem 26 that passes through the packing gland 27 supported on the cover 28 of casing 21. This stem is connected to a yoke 29 as by the aid of nuts 30 engaging opposite sides of the 100

yoke. The yoke is supported on a pair of bars 31, that are fastened at their other ends to a cross member 32. This cross member is arranged to be urged to the right when the water level recedes to a definite point.

For this purpose, it is carried at the end of an expansible tube 33, which screws into member 32 to communicate with a cavity 34 therein. This threaded end is free to move as the temperature of the tube 33 increases. Its left hand end 35 screws into a stationary head member 36 (see particularly Fig. 4). This member has a cavity 37 in communication with the fixed end 35 of tube 33. The arrangement is such that both ends of tube 33 are in communication with the interior of boiler 11—one end, such as the right hand end, above the normal water line in the boiler, and the other end, such as 35, below the normal water line.

Under such circumstances, if the axis of tube 33 be placed at or near the desired minimum water level, it is seen that as the level rises above this low water level, the tube will be filled with water; but if the level is reduced, then the tube fills with steam. Since this steam is at a higher temperature than the water, the tube 33 will then expand and open valve 21 for the admission of water to boiler 11.

In order to connect the tube 33 to the boiler in this manner, I provide piping 38 leading from a low part of boiler 11 to cavity 37; and I also provide piping 39 between the steam compartment in boiler 11 to cavity 34 in cross member 32 (see particularly Fig. 2). Piping 38 is purposely made rigid enough to provide a substantially rigid, stationary support for member 36; and piping 39 is of such a nature that it can give slightly to take up the movement of the right hand end of tube 33 due to its expansion and contraction.

Tube 33 is shown as slanting downwardly toward boiler 11. This is for the purpose of providing a draining effect for the water therein, as the water level recedes, and to prevent undesired trapping of liquid in the tube.

In order to guide the tube 33 in its expansion and contraction, I provide a series of spiders 40, providing a clearance aperture for the tube. These spiders are supported by the aid of rods 41 (four being shown in this instance) that pass through the spider arms and that are supported at their ends respectively in the member 36 and in the valve casing 21. Spacer sleeves 42 are arranged between the corresponding spider arms and these members 36 and 21, to hold the spiders in fixed spaced relationship. Since rods 41 can be made from steel or the like, temperature changes do not affect them materially, and there is therefore a decided and substan-

tial relative movement of the end of tube 33 with respect to the valve casing 21.

When the water level is at normal position, tube 33 is substantially entirely filled with water. It is therefore, in its contracted position, and closure 25 is tight against seat 24. When the level recedes, the water in tube 33 drains out, and steam replaces it. The tube 33 expands and urges yoke 29 to the right, valve closure 25 moves outwardly, and water is permitted to flow through pipe 15 from any source of water under pressure, such as a pump. As soon as sufficient water is fed to boiler 11, the steam from tube 33 recedes and is replaced by water. Tube 33 contracts, and pulls yoke 29 to the left, closing valve member 25. This interrupts the flow of water to boiler 11.

The door knob contour of valve closure 25 is of importance in the combination. Without it, there is a tendency for the valve to open and close alternately and in rapid succession. With the type of closure described, this hunting effect is entirely obviated. This is due in all likelihood to the fact that the path for the fluid is defined by comparatively smooth curved surfaces, and not by members having abrupt corners.

I also provide a novel low water alarm. I provide an electric switch structure 43 (Fig. 4) that serves to control an electric circuit when the water level reaches a dangerous low position. This structure 43 is supported by the aid of an extension 44 fastened to end head member 36. It includes a base 45 and a cover 46 through which the switch rod 47 projects, for its operation. This rod is arranged to be actuated by the aid of a lever 48 pivoted centrally on extension 44, and carrying an adjustable striker piece 49. When the water level recedes to a dangerous value, lever 48 is rotated in a counter-clockwise direction to an extent sufficient to push rod 47 inwardly and thereby to close a signaling circuit.

Lever 48 is arranged to be thus rotated in any desired manner; as for example by the aid of a pull rod 50 that is pivoted to the lower part of lever 48 and is connected at its opposite end to the cross member 32. Thus as cross member 32 moves to the right under the influence of a temperature increase of tube 33, rod 50 is pulled along with it.

In Fig. 1, I show a circuit 51 leading from switch 43 that controls a convenient visible or audible signal device 52. This device can be located at any convenient central location, remote from the boiler 11. When the level is low, the circuit for this device is completed through the source 53, and the operator at the central location is immediately apprised of the condition.

The particular switch structure utilized for device 43 is a matter of choice. In the present instance, I show rod 47 as carrying

an insulated contact disc 54 (Fig. 4), that contacts with a pair of spring fingers 55 (one only being shown) when rod 47 is pushed in. A spring 56 urges rod 47 back to its open position. The spring fingers 55 are insulated from each other and are connected respectively to opposite sides of circuit 51.

I claim:

1. In a water feed regulator for steam boilers, means arranged to be operated in response to a definite water level variation in the boiler, and a valve controlling the admission of water to the boiler, and actuated by said means, said valve being provided with a closure member of the door knob type, in which all the active surfaces thereof are smooth and curved.
2. In a water feed regulator for steam boilers, means arranged to be operated in response to a definite water level variation in the boiler, and a valve controlling the admission of water to the boiler, and actuated by said means, said valve having a closure member the active surface of which is of curved contour and devoid of all sharp edges.
3. In a feed water regulator for steam boilers, a substantially horizontal tube fixed at one end and capable of substantial expansion upon temperature rise, pipe connections from opposite ends of the tube respectively to below and above the water level in the boiler, a valve mechanism having a door knob closure member in which all the surfaces are smooth and curved mechanically connected to said expansible tube, a feed water pipe having a valve therein, and a by-pass around the said latter valve and controlled by the door knob closure member, whereby alternate manual and automatic control of the feed water regulation can be effected.

In testimony whereof I have hereunto set my hand.

JAMES C. KUTZNER.
